BOWLING PIN LIFTING AND RESETTING
APPARATUSCarl M. Weber and Thomas C. Pulvino, Rochester,
N. Y., assignors to Weber Machine Corporation,
Rochester, N. Y., a corporation of New York

Application January 28, 1947, Serial No. 724,792

7 Claims. (Cl. 273—42)

1

This invention relates to bowling pin setting mechanism. An object of the invention is the provision of generally improved and more satisfactory mechanism of this kind.

Another object of the invention is the provision of mechanism for resetting bowling pins quickly and effectively, with a minimum of lost motion and time.

These and other desirable objects are accomplished by the construction disclosed as an illustrative embodiment of the invention in the following description and in the accompanying drawings forming a part hereof, in which:

Fig. 1 is a diagrammatic fragmentary side elevation of the mechanism, especially showing the various positions of the upper and lower parts or portions of the pin spotter;

Fig. 2 is a fragmentary elevation of part of the mechanism shown in Fig. 1, illustrating additional details;

Fig. 3 is a side elevation of the construction shown in Fig. 2, viewed from a different direction;

Fig. 4 is a section taken substantially on the line 4—4 of Fig. 2;

Fig. 5 is a plan of the lower pin spotter;

Fig. 6 is a fragmentary plan of the lower pin spotter showing the jaws for holding the pin and the pneumatic cylinders for operating the jaws, and the piping connections;

Fig. 7 is a section taken substantially on the line 7—7 of Fig. 6;

Fig. 8 is a section taken substantially on the line 8—8 of Fig. 6;

Fig. 9 is a diagrammatic view illustrating the pneumatic connections of the lower pin spotter; and

Fig. 10 is a fragmentary side elevation of the entire mechanism illustrating diagrammatically some of the pneumatic connections and some of the electrical switch connections.

The same reference numerals throughout the several views indicate the same parts.

Referring now to Fig. 10, the rear end or pin end of the bowling alley surface is indicated at 50. Supported from suitable uprights (not shown) at the sides of the alley are various parts of the mechanism, including a guard member 55 extending across substantially the entire width of the alley and the gutters, and operated up and down by a pneumatic cylinder 56.

The mechanism includes a pin magazine indicated in general at 81, and a pin spotter or placing mechanism in two parts or halves, one of which may be called the upper pin spotter 82 and the other of which may be referred to as

2

the lower pin spotter 83, both of which are mounted for vertical movement with respect to the alley floor. Through various means not here shown, the pins are placed in the magazine. From the magazine they go into the two-part pin spotter, which is then lowered to place the pins on the floor of the alley, and the spotters 82 and 83 are again raised. However, after a player has rolled one ball, the pin spotters are lowered so that the lower spotter portion 83 is at the level of the necks of the standing pins, and it operates to grasp the necks of the pins and to pick up the pins which are left standing so that the fallen pins may be swept off of the alley, whereupon the pin spotter then lowers the pins which were left standing and places them again on the alley in their exact original positions where they were left after the rolling of the ball. The parts are now ready for the player to roll the second ball.

When the standing pins are lifted from the alley after the rolling of the first ball, for the purpose of sweeping the fallen pins from the alley, it is important that the standing pins be replaced on the alley in exactly the same positions from which they were picked up, even if the pins had been slightly displaced from their theoretical positions by the movement of other pins hit by the rolling ball. This is accomplished, in the present mechanism, by the parts shown especially in Figs. 1 to 9 of the drawings. The lower spotter, as shown in Fig. 5, contains ten holes, as indicated at 85 in Fig. 5. Each hole is of a diameter substantially larger than that of the bowling pin, to allow for substantial movement of the pin from its theoretical position, without interfering with the picking up of the pin. Associated with each of these holes are two jaws, a first jaw 90 (Figs. 6 and 7) having a smooth surface and being operated by a pneumatic cylinder 91, and a second jaw 92 having a serrated surface covered with rubber, this jaw being operated by the pneumatic cylinder 93. The jaw 92 is a rigid jaw in fixed relation to the piston of its cylinder 93. The first jaw 90, however, is a jaw which is pivoted at 94 to the slide 95 which is rigidly connected to the piston. As soon as the advancing slide 95 and jaw 90 contact with the neck of a pin left standing, the jaw 90 will pivot slightly on its pivot 94 and will push against a member 96 to actuate the micro-switch 97. Normally air pressure is delivered from the compressed air feed line 98 through the valve 99 to the cylinder 91. However, as soon as the micro-switch 97 is operated, this operates a solenoid

3
100, and the plunger 101 of the solenoid engages a rack 102 on the slide 95, thus locking this slide and its jaw 90 against further movement. Simultaneously, the plunger 101 operates the air control valve 99 to stop the flow of air to the cylinder 91 and start the compressed air flowing to the cylinder 93. Thus the other jaw 92 moves toward the neck of the standing pin and presses against the neck of the pin from the opposite side from that which is engaged by the jaw 90. The neck of the pin is thus firmly clamped between the two jaws, in its original position, due to the fact that the slide 95 is securely locked by the plunger 101 of the solenoid 100.

In any hole 85 in which no pin is left standing, the jaw 90 will continue its travel all the way until it engages the opposite jaw 92, since no pin is in the way to stop the motion of the jaw and thus to cause the micro-switch 97 to operate. When the jaw 90 comes into contact with the jaw 92, at the end of its travel, then the micro-switch will operate just as previously described.

When all of the jaw operations have been completed, the continued flow of air in from the feed line with no further movement of the pistons possible, will cause the air pressure to build up in the pneumatic system. This increase of air pressure will operate a pressure-responsive electric switch which energizes a circuit to operate the up-travel solenoid 104a of a solenoid valve 104 to permit flow of compressed air to the lower ends of the cylinders 105, thus raising the pin spotter 83 and carrying with it the bowling pins which were left standing, because of the clamping of the necks of these pins by the jaws 90 and 92. During the upward travel of the lower spotter, carrying the standing pins with it, a contact is made by the moving parts with micro-switch No. 3, shown in Figs. 1 and 2 of the drawings, and the closing of this switch starts the operation of a motor to operate the sweep mechanism so as to sweep the fallen pins from the alley. Micro-switch No. 3 as well as micro-switch No. 2 (designated also as switch 121) are operated by a lever as seen in Fig. 2 of the drawings, which engages first one end and then the other end of the notch 225 in rod 120. Upon completion of the sweeping cycle, the sweep mechanism will operate a switch which will operate the down-travel solenoid 104b to reverse the solenoid valve 104 so as to lower the pin spotter 83 again, in order to set the pins which were left standing after the roll of the first ball back onto the surface of the alley in their original positions.

As the pin spotter 83 comes down again at the completion of the sweeping operation, a notch 225 on the rod or shaft 120 (Fig. 1) which supports the spotter 83 operates the micro-switch 121, designated also as micro-switch No. 2. The operation of this switch de-energizes all of the locking solenoids 100 of the pin spotter 83, through suitable circuits, and at the same time operates an air-control valve to release air pressure from the far ends of the cylinders 91 and 93 and to supply compressed air to the near ends of the cylinders (that is, the ends nearest their respective pin holes 85) so that all of the jaws 90 and 92 are simultaneously moved back to their original position, unclamping any pins that have been clamped by these jaws and allowing the pins to remain on the alley floor. As soon as the air pressure builds up in the near ends of

5
10 all of these cylinders, the above mentioned pressure-responsive switch is operated which energizes the up-travel solenoid 104a so that the pin spotter 83 returns upward to its so-called stand-by position or interrupted position, indicated at C in Fig. 1.

The upper spotter 82 is provided with a series of ten holes for the bowling pins, vertically aligned with holes in the magazine 81.

The holes of the magazine and the holes of the upper spotter 82 are, of course, vertically aligned with the holes 85 in the lower spotter 83. The construction of the clamping jaws associated with these holes 85 in the lower spotter has already been described.

Pivoted latches 166 are mounted on the lower spotter 83 and project upwardly therefrom to engage the bottom of the upper spotter 82 to hold the two spotters a certain distance away from each other at the desired time. The magazine 81 has cam members 167 projecting downwardly from it to engage the latches 166 when the upper spotter and lower spotter both come up close to the magazine, so as to throw the latches 166 outwardly and allow the lower spotter to come up close under the upper. Whenever the lower spotter and upper spotter are away from the magazine, after once the lower spotter and upper spotter have been vertically separated from each other, the latches 166 will spring into position and prevent the two spotters from coming close to each other until they are raised to their high position near the magazine, when the latches will be released as above mentioned.

35 Referring now to Figs. 1 to 4 of the drawings, it is seen that the supporting posts 120 which support the lower spotter 83 from the pneumatic cylinders 105 which operate this spotter, are notched at 225 through a certain distance. Two 40 solenoids 227 operate plungers 226 to engage in these notches to operate as stops to limit the upward and downward movement of the spotter under certain conditions. When the spotter is in its highest position close to the magazine 81, the notches 225 are above the plungers 226 of the solenoids. In the first downward movement of both parts of the spotter when setting a frame of pins, the lower spotter 83 moves all the way down and the upper end of the notch 225 passes down below the latching plungers 226, so that the lower spotter goes all the way down to the low position shown in dotted lines at A in Fig. 1 but the upper spotter 82 at this time is retained a little above the lower spotter.

55 Separation of the lower spotter 83 from the upper spotter 82 sets the pins on the alley and also allows the latches 166 to snap to their latching position (under the influence of their springs) so that the upper and lower spotters will now be held separated from each other during the further movement of the parts until the time comes for setting up a complete new frame of pins. Now the rods 120 are raised by the air cylinders 105 to lift the spotters, the latches 166 still holding the upper spotter a substantial distance above the lower spotter, but during the upward movement, the iron-clad solenoids 227 operate the latching plungers 226 into the notches 225 of the rods 120 so that the plungers 226 engage the lower ends of these notches as the rods come up, stopping the movement in a position somewhat below the original position which is close to the magazine 81. The parts now remain in what is called the interrupted position or stand-by position, which position is indicated at C in Fig. 1.

If the player, on the roll of his first ball, has not made a strike, air cylinders 105 are operated to lower the spotters 82 and 83 as far down as they can come while the latches 226 are in the notches 225 of the shafts 120. These latches and notches prevent the spotters from going all the way down, but they go down to the spare pick-up position, the spotters being somewhat separated from each other at this time by the latches 166. The position to which the lower spotter descends (which is governed by the engagement of the plungers 226 with the upper ends of the notches 225 in the shafts) is a position in which the lower spotter 83 is located approximately at the level of the necks of the bowling pins which are left standing. The upper end of the notch 225 operates microswitch No. 2, which activates the air valve 99 to admit air to the cylinders on the lower spotter. Then, in the manner previously described, the jaws of the lower spotter will operate to grip all the standing pins at the necks of these pins, whereupon the spotters (both lower and upper) rise once more to the interrupted or stand-by position, determined by the engagement of the plungers 226 with the lower ends of the notches 225. When they reach this position, the lower ends of the notches 225 operate microswitches No. 3, which starts the operation of the sweep motor, if meanwhile the pressure switch activated by all the jaws on the lower spotter has been operated by the building up of the air pressure. This pressure switch is in series with micro-switch No. 3, so that if the pressure switch has not operated, the sweep motor will not start.

At the completion of the sweeping cycle, the sweep mechanism operates a switch (not shown) which operates the solenoid 104b controlling the air valve 104 so as to lower the spotter to set back on the alley the pins which were left standing and which were picked up by the spotter.

The spotter, when re-setting the pins which were left standing, goes down only to the so-called spare pick-up position shown in Fig. 1. The jaws on the lower spotter 83 are then opened, and the air pressure operates the pressure controlled switch to energize the up travel solenoid 104a so that the spotters 82 and 83 move upwardly once more to the interrupted or stand-by position indicated at C in Fig. 1.

The pins which were left standing after the roll of the first ball are now re-set in the alley in exactly the same positions which they previously occupied, and the player is ready to roll his second ball, which he now does.

It is seen from the foregoing disclosure that the above mentioned objects of the invention are admirably fulfilled. It is to be understood that the foregoing disclosure is by the way of illustrative example only, rather than by way of limitation, and that without departing from the invention, the details may be varied within the scope of the appended claims.

What is claimed is:

1. A bowling pin setting machine including a frame movable upwardly and downwardly, a pair of opposed jaws mounted for substantially horizontal movement in said frame, one of said jaws having a pivoted part, means for moving said one of said jaws toward a bowling pin until said pivoted part makes contact with said bowling pin, means controlled by movement of said pivoted part of said jaw for stopping further movement of said jaw and for commencing movement of the opposite jaw toward the opposite side of the bowling pin, and means for raising said frame

with the bowling pin grasped between said jaws to raise the pin from the bowling alley.

2. A bowling pin respotter including a movable frame adapted in one position to lie approximately parallel to a bowling alley floor at approximately the elevation of the necks of bowling pins standing on said floor, a series of sets of clamping jaws movably mounted on said frame, one set for each bowling pin, each set of jaws comprising two jaws both mounted for movement along one line and being elongated laterally in a direction substantially perpendicular to said line, one jaw of each set having a pressure-sensitive part thereon displaceable with respect to the remainder of the jaw, means for moving one jaw of each set toward the neck of a standing pin until it comes into contact with one side of said neck, while the other jaw of that set remains stationary, and means controlled by displacement of the pressure-sensitive part of the jaw for thereafter moving the other jaw of each set toward the opposite side of said neck to contact therewith and to clamp the neck against the first jaw.

3. A bowling pin setting machine including a spotter movable upwardly and downwardly relative to the alley floor, a plurality of openings in the spotter, one for each pin, two clamping jaws associated with each opening for clamping the neck of a pin between them to permit the pin to be raised from the alley floor when the spotter is raised, said jaws being arranged substantially parallel to each other and being elongated in lateral directions substantially perpendicular to their directions of movement and being mounted for independent non-simultaneous movement toward the neck of a pin, two fluid pressure cylinders, one operatively connected to each of said jaws, an electrically operated valve for controlling flow of fluid to the respective cylinders, and an electric switch operated by contact of the first jaw with the neck of the pin, to operate said valve to stop flow of fluid to the cylinder connected to the first jaw and to start flow of fluid to the cylinder connected to the second jaw.

4. A construction as defined in claim 3, further including clamping means cooperating with said first jaw to clamp the same against movement, and means operated by said electric switch to actuate said clamping means to clamp said first jaw, substantially simultaneously with operation of said valve to stop flow of fluid to the cylinder connected to said first jaw.

5. A bowling pin mechanism including a spotter movable upwardly and downwardly relative to the alley floor, a plurality of openings in the spotter, one for each pin, two clamping jaws associated with each opening and constituting a set of jaws for clamping the neck of a pin between them to permit the pin to be raised from the alley floor when the spotter is raised, the two jaws of each set being mounted for non-simultaneous movement toward each other and toward the neck of a pin interposed between the two jaws, two fluid pressure cylinders associated with each set of jaws, one cylinder being operatively connected to each of said jaws, a valve for controlling flow of operating fluid to one or the other of the two cylinders associated with each set of jaws, a clamp for clamping a first jaw of each set against further movement notwithstanding continued pressure applied by the fluid pressure cylinder operatively connected to the first jaw, a feeler mounted on and movable bodily with the first jaw of each set and also movable relative

to the jaw on which it is mounted when the jaw moves the feeler into contact with the neck of a standing pin, an electric switch operated by movement of said feeler relative to the jaw on which it is mounted, and means controlled by said electric switch for operating said clamp to hold the first jaw against further movement and concomitantly operating said valve to stop flow of fluid to the cylinder connected to the first jaw and to start flow of fluid to the cylinder connected to the other jaw of the same set of jaws.

6. A construction as defined in claim 5, in which said means controlled by said electric switch includes an electric solenoid having a plunger connected both to said clamp and to 15 said valve.

7. A bowling pin setting machine including a spotter movable upwardly and downwardly relative to the alley floor, a plurality of openings in the spotter, one for each pin, two clamping jaws associated with each opening for clamping the neck of a pin between them to permit the pin to be raised from the alley floor when the spotter is raised, said jaws being arranged substantially parallel to each other and being elongated in lateral directions substantially perpendicular to their directions of movement and being mounted for independent non-simultaneous movement toward the neck of a pin, fluid pressure means for moving one of said jaws toward the neck of

10 a free standing pin, a brake for stopping movement of said one of said jaws notwithstanding continued pressure applied by said fluid pressure means, a feeler mounted on said one of said jaws for engaging the neck of a free standing pin when the moving one of said jaws reaches the neck of the pin, electric switch means operated by said feeler for applying said brake to stop further movement of said moving one of said jaws notwithstanding continued pressure by said fluid pressure means, and means responsive to the stopping of said one of said jaws for initiating movement of the other of said jaws.
